UNITED STATES PATENT OFFICE.

WILLIAM M. SHEEHAN, OF ST. LOUIS, MISSOURI, ASSIGNOR TO COMMONWEALTH STEEL COMPANY, OF ST. LOUIS, MISSOURI, A CORPORATION OF NEW JERSEY.

CAR UNDERFRAME.

Application filed December 28, 1925. Serial No. 77,928.

My invention relates to an improved railway car underframe structure particularly adapted for use in hopper cars and other railway cars resembling hopper cars in not having continuous draft or center sills. My invention consists, broadly, in a provision of a car underframe with draft sills, a transverse bolster spaced from the outer end of the draft sills and serving to transmit the major portion of the buffing and pulling stresses to the car side sills which terminate at the bolster. Preferably the above described structure is completed and reinforced by the provision of a transverse member spaced inwardly from the bolster and to which the draft sills extend. My underframe is adapted to be mounted upon trucks of the type described in Patent No. 995,560, issued June 20, 1911, to H. M. Pflager, and more particularly described and explained in the co-pending Pflager application, Serial No. 34,706, filed June 3, 1925, in which the car underframe is pivotally assembled with the car truck at the sides of the truck.

The main object of my invention is to eliminate diagonal members connecting the draft and side sills of the underframe as have previously been used in underframes of this type, and to transfer the stresses which have been taken care of by such diagonal members by means of the transverse bolster. An additional object of my invention is to embody the structure described in a one-piece casting thereby securing a maximum degree of strength for a given weight of material.

In the accompanying drawings which illustrate a selected embodiment of my invention—

Figure 1 is a top view of my improved underframe in the form of a one-piece casting.

Figure 2 is in part a longitudinal vertical section on line 2—2 of Figure 1 and in part a side elevation.

Figure 3 is in part a vertical transverse section on line 3—3 of Figure 1, and in part an end elevation.

Figures 4 to 8 are sections taken respectively on lines 4—4, 5—5, 6—6, 7—7 and 8—8.

Figure 9 is a section taken on line 9—9 of Figure 2.

Figure 10 is a section taken on line 10—10 of Figure 1.

The main elements of the underframe are the side sills 1, bolster 2, draft sills 3, and a transom member 4 spaced inwardly from the bolster 2. The draft sills 3 extend forwardly of bolster 2 and terminate at a striking plate 5 and coupler carrier 6. The draft sills are box-shaped in cross-section and the bolster 2 is also box-shaped in cross-section. The outer side wall 3^a of each draft sill is offset at the bolster, but is parallel with the center line of the car throughout its length, the inner side wall 3^b of the draft sill is inclined outwardly from the bolster rearwardly for a portion of its length.

The draft sills terminate with member 4 which forms a support for the bottom of the hopper and floor plates and this member 4 is reinforced by the spaced walls of the draft sills. The lower walls of the draft sills merge with a suitable flange 7 which extends along the bottom of member 4 between the draft sills and the side sills.

The box-shaped bolster is provided with transverse walls 8 at intervals and bearings 9 are provided on the lower wall of the bolster for being pivotally assembled with the side frame of the truck. The upper and lower walls of the draft sills and bolster are connected with each other by curved flanges 11 of substantial area so as to suitably absorb the buffing and other stresses transmitted from the draft sills through the bolster or vice versa.

The side sills 1 terminate at the bolster and are provided with suitable pads 10 for attaching the car superstructure, airbrakes, and operating mechanism, etc. These pads are more particularly described and explained in my co-pending application, Serial No. 76,479, filed December 19, 1925.

The upper faces of the draft sills, bolster, side sills, member 4 and the upper flanges 11 connecting these elements are all located in substantially the same horizontal plane, thereby forming a platform-like surface for mounting such equipment as is usually placed beneath the hopper end floor. Obviously the corners of the car underframe may be completed by suitable light structural members such as will be necessary to carry the car ladders and support the upper end of the car hopper floor. Such members form no part of my present invention but are illustrated in my copending application Serial No. 79,782, filed January 7, 1926.

The above described construction provides spaced box-shaped draft sills from the end of the hopper to the end of the car and extending substantially beyond the ends of the side sills. These draft sills are braced by and transfer their stresses to a box-shaped bolster which carries the superimposed load near its ends and distributes the buffing and pulling loads to the side sills, the latter distribution being assisted materially by the transom 4.

Obviously, the details described may be varied without eliminating the principles of my invention as claimed.

15. I claim:

1. In a one piece car underframe casting, a bolster, and bearings on said bolster near the ends thereof for pivotally engaging a truck, and bolster reinforcing members extending transversely of the bolster adjacent to said bearings.

2. In a one piece car underframe casting, a box-shaped bolster, and bearings on said bolster between its side walls near the ends thereof for pivotally engaging a truck, and bolster reinforcing members extending transversely of the bolster adjacent to said bearings.

3. In a one piece car underframe casting, 30 a bolster, bearings on said bolster near the ends thereof for pivotally engaging a truck, and draft sills projecting outwardly from said bolster intermediate said bearings, and bolster reinforcing members extending transversely of the bolster adjacent to said bearings.

4. In a one piece car underframe casting, a bolster, bearings on said bolster near the ends thereof for pivotally engaging a truck, 40 and box-shaped draft sills projecting outwardly from said bolster intermediate said bearings, and bolster reinforcing members extending transversely of the bolster adjacent to said bearings.

45. 5. In a one piece car underframe casting, a box-shaped bolster, bearings on said bolster, near the ends thereof, for pivotally engaging a truck and box-shaped draft sills projecting outwardly from said bolster intermediate said bearings, and bolster reinforcing members extending transversely of the bolster adjacent to said bearings.

6. In a car underframe, a box-shaped bolster, bearings on said bolster near the ends thereof for pivotally engaging a truck, box-shaped draft sills projecting transversely of said bolster intermediate said bearings, and arcuate flanges of substantial radius connecting the upper and lower walls of said bolster and draft sills.

7. In a car underframe, side sills terminating short of the end of the underframe, a bolster connecting the ends of said side sills, a cross-member connecting the said side sills at a point spaced from their ends and form-

ing a support for the lower edge of a hopper, and draft sills extending from said member outwardly of the car past said bolster.

8. In a car underframe, side sills terminating short of the end of the car, a bolster connecting the ends of said side sills, bearings on said bolster near said side sills for pivotally engaging a truck, and draft sills extending forwardly of said bolster.

9. In a car underframe, side sills terminating short of the end of the car, a bolster connecting the ends of said side sills, and spaced draft sills, each box-shaped in cross-section, extending outwardly from said bolster.

10. In a car underframe, side sills terminating short of the end of the car, a bolster connecting the ends of said side sills, and spaced draft sills, each box-shaped in cross-section, extending outwardly and inwardly from said bolster.

11. In a car underframe, side sills terminating short of the end of the car, a bolster connecting the ends of said side sills, and spaced draft sills, each box-shaped in cross-section, extending outwardly and inwardly from said bolster, the outer wall of each of said draft sills being offset at said bolster.

12. In a car underframe, side sills terminating short of the end of the car, a bolster connecting the ends of said side sills, and spaced draft sills, each box-shaped in cross-section, extending outwardly and inwardly from said bolster, the outer wall of each of said draft sills being located farther from the corresponding inner wall behind the bolster than in front of the bolster.

13. In a car underframe, side sills, a bolster, a transverse member spaced from said bolster forming the end of the hopper opening and extending between said side sills, and draft sills extending from said cross-member past said bolster to the end of the car.

14. In a car underframe, side sills, a box-shaped bolster, bearings on the latter near its ends for pivotally engaging a truck, a transverse member spaced from said bolster, forming the end of the hopper opening and extending between said side sills, and box-shaped draft sills extending from said cross-member past said bolster to the end of the car.

15. In a car underframe, side sills terminating a substantial distance from the end of the underframe, a bolster connecting the ends of said side sills, draft sills extending from the end of the underframe past said bolster and then diverging in part to the hopper opening.

16. In a car underframe, side sills terminating a substantial distance from the end of the underframe, a bolster connecting the ends of said side sills, draft sills extending

from the ends of the underframe past said bolster and each comprising an inner wall inclined outwardly from the bolster to said member and an inner wall parallel with the 5 center line of the car and offset at said bolster.

17. In a car underframe, side sills terminating short of the end of the underframe, a bolster connecting the ends of said side 10 sills, and an inclined cross member, the lower portion of which extends in a straight line between said sills and the upper portion of which is inclined toward the ends of the car from each side sill inwardly.

18. In a car underframe, side sills terminating short of the end of the underframe, a bolster connecting the ends of said side 20 sills, a cross-member connecting the said side sills at a point spaced from their ends and forming a support for the lower edge of a hopper, and draft sills extending from said member outwardly of the car past said bolster, the body of said member being straight between said draft sills and outside of said 25 draft sills being curved toward said side sills and toward the middle of the car.

19. In a car underframe, side sills terminating short of the ends of the underframe, a bolster connecting the ends of said side sills, draft sills extending outwardly 30 beyond said bolster, and superstructure supporting members carried by the ends of said sills.

20. In a car underframe, side sills terminating short of the end of the car, a bolster connecting the ends of said side sills, bearings on said bolster near said side sills for pivotally engaging a truck, draft sills extending forwardly of said bolster, and superstructure posts carried on the ends of 40 said side sills.

21. In a hopper car underframe, a bolster, a transverse member spaced inwardly from said bolster, draft sills between said bolster and member and including portions 45 diverging rearwardly, said member extending outwardly and rearwardly from said draft sills to the sides of the underframe.

In testimony whereof I hereunto affix my signature this 21 day of November, 1925.

WILLIAM M. SHEEHAN.
